UNITED STATES PATENT OFFICE.

DAVID C. NELSON, OF QUINCY, AND WALTER R. EATON, OF CAMBRIDGE, MASSACHUSETTS.

TROLLEY-CARRIER.

SPECIFICATION forming part of Letters Patent No. 430,675, dated June 24, 1890.

Application filed March 25, 1890. Serial No. 345,276. (No model.)

To all whom it may concern:

Be it known that we, DAVID C. NELSON, of Quincy, in the county of Norfolk, and WALTER R. EATON, of Cambridge, in the county of Middlesex, and State of Massachusetts, citizens of the United States, have invented certain new and useful Improvements in Trolley-Carriers; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to improvements in "trolley-carriers" so called, adapted for use in connection with electric cars for street-railways having the overhead system and employed to support the trolley-wheel and maintain the latter in rolling contact with the trolley-wire, thereby serving to conduct the electric fluid from said wire to the motor.

Our invention comprises two features. One consists in a double arm trolley-carrier and in an arrangement of parts whereby the pressure of the trolley-arms—the two being oppositely disposed—can be adjusted and controlled to suit varying conditions of the wire; and, further, to cause each of said trolley-carriers to contact with the wire in turn when the car is changed in its direction of travel. By thus providing two reversely-disposed trolley-carriers no occasion exists for shifting the position of the said trolley-carriers, as is now practiced, it merely being necessary to raise one and similarly lower the other trolley-carrier.

The second feature of our present invention is embodied in a pivotal extension in which is journaled the trolley-wheel and further provided with spreading prongs or automatic "finders" so called, whereby the trolley-wheel, when disengaged from the trolley-wire, can readily be replaced and the circuit broken by such displacement again closed through the motor.

The drawings accompanying this specification represent in Figure 1 a side elevation of an electric street-car furnished with a trolley-

carrier embodying our invention. Fig. 2 is a plan of the mechanism for regulating the position of the trolley-carriers against the wire. Fig. 3 is a perspective view of the automatic finder enlarged. Fig. 4 is a similar view of the foot of the trolley-carrier. Fig. 5 is an end view of the car and trolley-carriers. Fig. 6 shows in perspective the three parts which comprise the spring-dog. Fig. 7 is a perspective view in detail of the toothed rack.

The first portion of our invention comprises two trolley-arms, in lieu of one, as now in general use. When the car comes to the end of its route and its direction in travel changed it becomes necessary to shift the position of the trolley-arms to render the one lately in service inactive, and to cause the other to become active and bear against the trolley-wire. The latter is shown at 2, and an electric street-car at 3, which is equipped with a rod 4, extending longitudinally of the car and movable endwise of the roof by means of two handles or terminals 5 at each end. Said rod is mounted between anti-friction rollers 6 in pairs secured exteriorly of the car-top to insure easy movement when so desired. Centrally of the car is mounted twin standards or housings 7, which support a short shaft 8. Rigidly secured thereto are the trolley-carriers 9, duplicates in construction, but oppositely disposed. One of these is employed when the car moves in one direction, the other when such direction is reversed. Consequently, the position of these arms must be changed at the end of each trip unless the car is shifted end for end by a turn-table. To effect this change and movement in the position of the trolley-arms, and in order to cause each to contact with the trolley-wire at proper determined times, we have arranged the following mechanism: Lateral or side movement occasioned by deviation of the trolley-wire above the center of the road-bed by the swaying of the car or otherwise is compensated for by fastening upon the shaft 8 two short arms 23 forked at their upper ends, and provided with an offset, so that the two trolley-carriers are in the same alignment and beneath the trolley-wire. The ends of said arms, as before premised, are forked and have springs 24 bolted laterally thereupon. The lower end

of the trolley-carrier proper extends below its pivot at 26 and acts against one of the springs depending upon the deviation of the carrier sidewise. Such departure from the proper alignment causes a leverage against one of said springs, and when the cause for such deviation ceases the action of the spring then pressed upon forces the carrier to resume its normal position. The trolley-carriers are pivotally attached to the arms 23, the pivots being at right angles to the shaft 8. Firmly attached to the shaft 8 is a pendent spring-lever 12. The latter is preferably a strong spring, and its elasticity serves to force the trolley-carrier up against the wire. Said lever terminates in a fork engaging in a plate 13. This is connected and moves with the rod 4. Mounted on said rod and preferably in proximity to the ends of said plate are set two oppositely-disposed spring-dogs 14. These are transversely of and adjustable with respect to said rod. Laterally of the said plate 13, and in vertical position, are placed two toothed racks 15, which co-operate respectively with the dogs before mentioned. These spring-dogs are set at an angle of about ninety degrees with each other in such position that both can be held removed from their racks, and thus permit free thrust or pull upon the rod 4 when the carriers are to be shifted in position. From their position it is evident only one dog can be utilized at the same time.

In Fig. 7, looking at the teeth 27 upon the rack it will be noticed that the active faces 28 against which the dogs rest are vertical. As a consequence there is a liability of the rod 4 twisting or turning, due to jar from the movement of the car. This would produce disengagement of the active dog and rack 40 and permit the trolley-carrier to change its position. To obviate this the lower portion of the face of each tooth is cut away, forming an overhanging lip or guard 29; hence, to disengage the dog a slight endwise movement or thrust must be given the rod in order to clear the dog from the guard. Axial motion of the rod 4 can then be effected and the dog placed in an inactive position. The dogs we have mentioned as spring ones. These are constructed as follows: A collar 30 and a disk 31, with a spur 32, both centrally bored and adapted to be adjustably secured upon the rod 4. Between said disk and collar is fastened a plate-spring 34, with a finger or prong, which serves as the active holding part of the dog; but since its inherent strength does not suffice it is backed or supported by the spur 32 cast upon the disk. Further, the spring projects sufficiently beyond the disk to wipe by the respective teeth of the rack, since it is free to yield to advance, but is locked against reverse motion, for the reason that the spur rigidly supports it.

65 The operation of this portion of our invention is readily perceived. By means of the terminals or handles 5, pivotally hung at 35

to the rod 4, the conductor has perfect control of the trolley-arms. Thus, by reference to Fig. 1, the right-hand carrier is in contact with the wire. To reverse the position of said arms he grasps a handle and partially turns the rod 4 until the now active dog is disengaged from its holding-rack. Then by axial movement of the rod he causes the other dog to engage its rack. A pull or thrust now exerted upon said rod 4, and dependent upon which end of the car he stands, causes the spring-dog to wipe over the teeth of the rack and prevents any back play. Such movement causes the spring-lever 12 to swing in direction of arrow 2, which simultaneously causes the trolley-carrier now in contact with the wire to be depressed, while the other is raised and brought against the trolley-wire. When this result is accomplished the rod 4, by means of the handle, is released, and the now active trolley-arm is held under proper pressure against the wire. To obviate frictional contact, which occurs between the plate and the forked end of the actuating-lever when endwise movement of the plate occurs, small anti-friction rollers 36 are inserted at the ends of each slot containing one of the fingers of the lever. Hence a rolling friction occurs, and the rod 4 is operated with very little difficulty.

The other feature of our invention consists in a finder for a trolley-carrier, whereby the trolley-wheel, when disengaged from the trolley-wire, as in rounding a curve, can be caused to readily pick up and again be made to contact with said wire. To accomplish this result easily and effectively, we have furnished the end of the trolley-arm 9 with a pivotal extension 17, in the upper extremity of which is mounted the trolley-wheel 18. Furthermore, extending from this extension which straddles the wheel are two flaring arms or finders 19. These are positioned obliquely of the longitudinal axis of the trolley-carrier, and preferably at such an angle that the said finders lie some little distance below the wire when the wheel is in contact therewith. This extension of the trolley-carrier is pivoted about midway of its length, while its lower end 20 is spring-actuated at 21. In lieu of a spring a counterbalance-weight may be hung upon this lower end. In the event of said pivotal extension being used on the ordinary trolley-carrier, the cord which now serves to control said carrier could be attached to the lower end 20 and the same result be effected as would be produced by the spring. In either case the said extension is tilted upward, when free of the wire, into the position shown on the left side of Fig. 1. This lower part is semi-cylindrical, and, being adapted to lie against the under side of the trolley-carrier proper, compresses the spring when the wheel is on the wire. This serves to keep the pivotal extension in alignment with the main arm, as likewise stiff and rigid. However, the moment pressure of the wheel against the wire ceases,

occasioned by the wheel leaving the latter, the spring 21 is free to perform its duty. Such action thrusts the lower end portion 20 away from the arm, when the extension assumes an upright position and the finders now stand vertical, extending above the wheel, and are in readiness to engage the wire and lead the trolley-wheel back to its proper place upon the wire. The moment the normal pressure is resumed between said wire and wheel the extension is again aligned with the carrier proper, the spring 21 compressed, and the finders now assume a horizontal position, which permits them to pass freely beneath the transverse wires which uphold and support the trolley-wire.

What I claim is—

1. In combination with an electric car, a pivotal trolley-carrier secured in a standard placed upon the roof, an actuating-lever rigidly attached to said carrier, a rod longitudinally of and above said car connecting with the lever, and mechanism for holding said rod in any desired position, substantially as stated.
2. The combination, with an electric car, two oppositely-disposed trolley-carriers rigid on a common shaft, and a rod lengthwise of the car movable endwise thereof, of a pend-30 ent lever, which unites said carriers with the rod, and mechanism for holding the rod in any desired position, composed of two toothed racks secured to the car-roof and two dogs transversely upon said rod, all operating sub-35 stantially as herein set forth and described.

3. A trolley-carrier furnished with a pivoted terminal in which the trolley-wheel rotates, the said terminal being capable of tilting on its pivot, substantially as and for the purpose set forth.

4. A trolley-carrier for electric rail service composed of a carrier-arm proper and a pivotal terminal in which the trolley-wheel revolves, said terminals being furnished with finders, substantially as specified.

5. The combination, with an electric car and a trolley-carrier thereupon, of a pivotal terminal, the projecting prongs or finders formed at the upper end, and the lower end adapted to overlap and bear against the trolley-carrier, and the spring interposed therebetween, all operating substantially as de-50 scribed.

6. The combination, with an electric car, two simultaneously oppositely rocking trolley-carriers, and a spring-lever which controls said carriers, of a rod 4, movable endwise of the car, a spring-dog upon said rod, a plate interconnecting said rod with the lever, and a rack secured to the car, the teeth 55 forming said rack having projecting guards, substantially as described.

In testimony whereof we affix our signatures in presence of two witnesses.
